UNITED STATES PATENT OFFICE.

JOHN CARROLL, OF CHICAGO, ILLINOIS.

CURTAIN-ROD POINT.

No. 853,680.

Specification of Letters Patent.

Patented May 14, 1907.

Application filed March 8, 1906. Serial No. 304,963.

To all whom it may concern:

Be it known that I, JOHN CARROLL, a citizen of the United States, residing at Chicago, in the county of Cook and State of Illinois, have invented certain new and useful Improvements in Curtain-Rod Points; and I do hereby declare the following to be a full, clear, and exact description of the invention, such as will enable others skilled in the art to 10 which it appertains to make and use the same.

My invention relates to a novel construction in a temporary point for curtain rods, the object being to provide a device of this 15 character which may be temporarily mounted upon the end of a curtain rod in order to enable the same to be readily inserted through the hem of a curtain or the like to be hung thereon, and consists of the features of 20 construction hereinafter fully described and claimed.

In the accompanying drawings illustrating my invention: Figure 1 is a central longitudinal section of a curtain rod point constructed in accordance with my invention showing the same disposed upon the end portion of a hollow curtain rod of the kind most generally employed. Fig. 2 is a transverse section of the same on the line 2—2 of Fig. 1.

30 The sharp ends of curtain rods render it a relatively difficult operation to insert such rod through the hem of a lace or other curtain by reason of the fact that such sharp ends and edges catch in the fabric and frequently cause the same to tear. This is particularly true of the starched or otherwise stiffened lace curtains so generally employed. To overcome this difficulty I provide a temporary point for curtain rods which consists of 40 a conical body portion A of relatively larger diameter than the curtain rod and which is provided at one end with a concentric slightly exteriorly tapered shank B, the latter being provided with a central longitudinal 45 recess C terminating at its inner end adjacent the pointed end of the body portion A. The said shank B is of smaller diameter than the largest diameter of said body portion A, the latter being provided adjacent its point 50 of juncture with said shank B with an annu-

lar flange D concentric with said shank A and between which and said shank is an annular recess E.

The curtain rods most generally employed consists of light butt joint tubing of standard 55 gages. My device is made in various sizes to fit the various gages of tubing employed, and the shank B thereof is made slightly larger in its greatest diameter than the inner diameter of the tube G so that when said 60 shank is inserted in one end thereof said tubing will be slightly expanded at said end and thus hold said point frictionally thereon.

The annular recess E is adapted to receive the wall of the tubing and thus completely 65 cover the sharp edge thereof so that the rod may be moved backward and forward through the hem of a curtain or the like without danger of catching therein and injuring the fabric in any degree.

70 The central recess C is adapted to receive the ends of solid metallic curtain rods also frequently employed so that each point will be adapted for a certain gage of tubular curtain rod and likewise a given gage of solid 75 metallic curtain rods.

My device is simple, efficient and cheap.

I claim as my invention:

1. A curtain rod point comprising a relatively conical body portion having a concentric shank of smaller diameter provided with a central recess, and an annular flange concentric with and overhanging said shank disposed at the rear end of said body portion at its point of juncture with said shank.

80 2. A curtain rod point comprising a relatively conical body portion, a shank on the larger end of the same concentric therewith and of smaller diameter than the largest diameter of said body portion, and an annular flange disposed upon the rear end of said body portion concentric with and overhanging said shank, there being an annular space 85 between said flange and said shank.

90 3. A curtain rod point comprising a relatively conical body portion, a shank on the larger end of the same concentric therewith, and of smaller diameter than the largest diameter of said body portion, and an annular flange disposed upon the rear end of said 95 100

body portion concentric with and over-hanging said shank, there being an annular space between said flange and said shank, and said shank being provided with a central recess terminating at its inner end in said body portion adjacent the smaller end thereof.

In testimony whereof I have signed my name in presence of two subscribing witnesses.

JOHN CARROLL.
